GEORGE M. NELSON

BY *George M. Nelson*

ATTORNEYS.

UNITED STATES PATENT OFFICE.

GEORGE M. NELSON, OF MONTEREY, CALIFORNIA.

CONCRETE REINFORCEMENT.

Application filed May 5, 1924. Serial No. 711,075.

To all whom it may concern:

Be it known that I, GEORGE M. NELSON, a citizen of the United States, and a resident of Monterey, county of Monterey, State of California, have invented a new and useful Concrete Reinforcement, of which the following is a specification.

This invention relates to the reenforcement of concrete, either when used for walls, columns, floors, concrete blocks, also fence and telegraph posts, railway ties, and concrete lumber generally.

The objects of my invention are to provide a reenforcement unit which may be assembled and interlocked in skeleton structure to suit the particular usage and rigidly secured together by the solidification of the concrete on all sides around it; Also, such a unit which will interlock with similar units without the necessity of wiring together before pouring the concrete;

Also such a reenforcement which will present a series of imbedded metal arches within the concrete to stiffen it and make it more resistant to shocks and in case of walls or floors, etc., of greater resistance to a force applied perpendicular to the plane of the wall or floor;

Also a means of reinforcing the extreme corner of posts, columns, projecting wall corners, etc., and of firmly bracing such corners against the main reenforcements within the body of the concrete.

I secure the objects above outlined by the concrete reenforcement as shown in the accompanying drawings and in which:—

Figure 1 is a cross section of a concrete post or column reinforced according to my invention, and the reenforcement is shown of a size suitable for a four-inch post or wall;

Figure 2 is a reduced section of a portion of a wall, floor, or block with my assembled reenforcing units imbedded therein;

Figure 3 is a perspective elevation of one of my corner units showing the perforations, ribs and interlocking lugs;

Figure 4 is a similar perspective of the lower end only of a similar unit showing the straddling lugs on its lower edge adapted to engage the upper edge of the unit shown in Figure 3;

Figure 5 is a section of Figure 3 as seen from the line 5—5 thereof;

Figure 6 shows in cross section a modified form of my arched plate.

In taking up a detailed description of the drawings it should be noted that my reenforcement embraces three cooperating features:

(1) Arched or channel like interlocking plates (1).

(2) Straight tying plates (2).

(3) Straight corner plates (3).

The arched and tie plates are completely enclosed within the concrete mass (4) and the corner plates extend to the outer surface and have a flange (5) formed on the extreme edge to make a slightly curved exposed metal corner to the block, post or outside wall corner.

In practice the corner plates (3) are made integral with the adjacent arched plate as indicated in the figures.

The plates are in effect strips or channel forms several feet in length and all are preferably perforated and ribbed as shown in Figure 3 respectively at (6) and (7).

The ribbing and perforating of the plates extend to within about 6 inches of the ends and may be modified considerably from the arrangement shown, depending on the size of the plates and their particular use, the particular arrangement being determined from the stresses which the concrete will be subjected to when finished.

The plates join endwise by simple straddling lugs (8) on one plate which engage opposite sides of the plate below and the plates engage along their vertical edges by lugs or tongues (9) which enter slots (10) along the edges of adjacent plates when assembled.

In place of the lugs (9) being formed on the plates as shown, additional slots (11) may be used but in this case separate tying strips would be required to engage the slots and which is avoided by having the lugs projecting from one plate to engage the slots of the next.

When assembling my reenforcement for a wall as shown in Figure 2 the cross tie plates (2) being formed with offset slotted vertical margins (12) are adapted to receive through their slots (10') the same lug (9) from one arched plate after having passed the slots in the next arched plate.

The slots 10' in the margins 12 of plates

2 correspond precisely to the slots 10 of Figure 1, being vertically spaced to receive the lugs 9 of the abutting plate in the same manner.

5 The lugs or tongues (9) are preferably so shaped that they will resiliently spring into the slots of the adjacent plates without the necessity of bending them over, so as to hold the assemblage together until the 10 concrete is set around the same.

When pouring a wall or column having outside corners, or in molding a building block, the forms touch the corner flanges (5) as indicated in Figure 2 where a portion of a form is shown in position at (13).

15 If the flange (5) should not fit tightly against the inner sides of the form the concrete will in some places form a shank corner outside of the flange, but this is readily removed after the form is taken 20 down as it is my intention to expose a slightly rounded metal corner as shown.

25 My reenforcement may be of any size or thickness to suit whatever concrete construction is undertaken, and instead of the arched plates being curved they may be formed by angular bending as shown in Figure 6 and still realize the feature of the series of im- 30 bedded arches which my reenforcement provides. Also it should be observed that my construction makes it possible to core the blocks or walls between the reinforcing elements as indicated in Figure 1 if desired.

I claim:

1. A concrete reenforcement comprising a 35 series of interlocked arched metal plates, said plates being perforated and having means for interlocking along their edges to form a continuous corrugated structure.

2. A concrete reenforcement comprising a 40 series of arched metal plates, said plates being perforated and ribbed transversely to the arched surface and having means for interlocking along their edges to form a continuous corrugated structure. 45

3. A reenforcing unit for concrete construction comprising a plate having lugs extending from its edge and offset in opposite directions and adapted to engage opposite sides of a plain edged abutting plate. 50

4. A reenforcing unit for concrete construction comprising an arched plate adapted for interlocking with similar plates to form a wall reinforcement, and a web extending from the arched plate adapted to 55 reinforce an outside corner of the structure.

5. A reenforcing unit for concrete construction comprising an arched and perforated plate having means at the legs of the arch adapting the plate for locking at similar points with similar plates to form a continuous corrugated structure and with the perforations of the plates forming passages 60 for the concrete interlocking both sides of the plates.

GEORGE M. NELSON.
